UNITED STATES PATENT OFFICE

CLEO BENNETT, OF NORTH TONAWANDA, NEW YORK

DESIGN FOR A DOLL OR SIMILAR ARTICLE

Application filed June 4, 1931. Serial No. 40,079. Term of patent 7 years.

To all whom it may concern:

Be it known that CLEO BENNETT, a citizen of the United States, and resident of North Tonawanda, in the county of Niagara and State of New York, has invented a new, original, and ornamental Design for Doll or Similar Article, of which the following is a specification, reference being had to the accompanying drawing, forming part thereof, in which,

Fig. 1 is a front elevational view of a doll embodying my new design; and
Fig. 2 is a side elevational view thereof.

I claim:

The ornamental design for a doll or similar article, substantially as shown.

Dated, May 28th, 1931.

CLEO BENNETT.
